UNITED STATES PATENT OFFICE.

ALFRED W. BRUCE, OF NEW YORK, N. Y.

LOCOMOTIVE BOILER.

Application filed January 11, 1927. Serial No. 160,330.

My invention relates to boilers of the locomotive type, and of the class thereof in which the sides of the fire box and combustion chamber are formed of a plurality of 5 water tubes, an instance of which is exemplified in the patent of J. M. McClellon, No. 1,580,063, April 6, 1926. My present invention is particularly directed to the adaptation of a boiler of the type specified, for operation under comparatively high steam pressure, and to effecting a reduction of the weight and dimensions of the boiler to a substantial extent. A characteristic feature of 10 my invention is the application of separate circulation systems for the fire box and for the barrel of the boiler.

The improvement claimed is hereinafter fully set forth:

In the accompanying drawings; Figure 1 20 is a vertical longitudinal central section through a boiler embodying my invention; Fig. 2, a half plan view thereof; Fig. 3, a vertical transverse section, the right hand half being taken on the line III, III of Fig. 25 1, and the left half on the line III^a, III^a thereof; Fig. 4, a similar section, the right hand half being taken on the line IV, IV of Fig. 1, and the left hand half on the line IV^a, IV^a thereof; and Fig. 5, a similar section 30 on the line V, V of Fig. 1.

In the practice of my invention, referring descriptively to the specific embodiment thereof which is herein exemplified, the improved locomotive boiler thereof comprises 35 three main sections; the fire box, A, the boiler barrel, B, through which extends a plurality of fire tubes, 3^b, and the smoke box, C, and a combustion chamber, D, is located in the forward portion of the fire box. The 40 mud ring, 2, of the fire box, is hollow, and forms the bottom support of a plurality of water tubes, 3, which are set closely together, forming the side walls of the fire box, and are connected, at their upper ends, with a drum, 4, which extends horizontally and forwardly over the barrel, B, in this instance to a front header, 12, with which it communicates, which header communicates with the barrel, B. The mud ring, 2, at its rear end, 45 supports, and communicates with, the back head, 5. Arch tubes, 6, which support a fire brick arch, 7, are connected to the front of the mud ring, and extend upwardly and rearwardly to the back head, 5. The upper 50 surface of the grate, 8, lies approximately in

the plane of the top of the mud ring. The forward limb of the mud ring is apertured for communication with a feed water connection, 10, leading into the barrel, B, to the forward portion of which, water is supplied 60 through a feed pipe (not shown) provided with a check valve, in the ordinary manner.

The water tubes, 3^a, of the combustion chamber, D, form continuous walls with the fire box water tubes, 3, and conform in curvature therewith, above the axial line of the barrel, below which they are curved on arc struck substantially radially from said axial line. The water tubes, 3 and 3^a, are connected, at their tops, to the drum, 4, and, at 70 their bottoms, to the mud ring, 2, and to a feed water member, 11, respectively. The member, 11, extends forwardly to a connection with the barrel, B, and provides a water passage from said barrel to the bottoms of 75 the combustion chamber water tubes, 3^a, while a connection, 10, independently supplies water from the barrel, B, to the mud ring, 2, and, through the mud ring, to the fire box side water tubes, 3, the arch tubes, 6, and the back head, 5.

Headers, 12 and 13, are located at the front and rear ends, respectively, of the barrel, B. The drum, 4, extends through both headers, but is in communication with the front 85 header, 12, only, through ports, 14. Two smaller drums, 15, 15, are disposed on the opposite sides of the drum, 4, exterior to the barrel, said smaller drums extending from the header, 12, to the header, 13, and being 90 in communication with the barrel through said headers.

A suitable throttle valve, 16, is located adjacent to the front of the drum, 4, and controls communication between said drum and 95 steam supply pipes, 17, leading therefrom to a superheater, 18, or to the valve chests of a locomotive, as the case may be. If desired, a vertical longitudinal baffle plate, 19, may be fitted in the portion of the drum, 4, that extends through the fire box and combustion chamber, to prevent interference of the currents of water rising from the tubes on opposite sides thereof.

In the operation of a boiler of the construction hereinbefore specified, steam generated in the back head, 5, and side water tubes, 3 and 3^a, flows forwardly through the drum, 4. Steam generated in the barrel, B, rises 100 through the header, 13, into the smaller 110

drums, 15, flows forwardly through them into the header, 12, and thence enters the forward end of the drum, 4, through the ports, 14. There is thus a flow of steam forwardly from the water tube walls of the fire box, through the drum, 4, to the throttle valve, 16, and a flow of steam from the barrel, rearwardly through the drum, 4, to the throttle valve. Steam from both sources, 10 traverses past the throttle valve, through the pipes, 17, to the superheater, 18, or directly to the valve chests of the locomotive. There is likewise an independent circulation of steam generated in the barrel from the rear 15 to the forward ends thereof, through the lateral drums, 15, 15.

A wrapper sheet, 20, which encircles and houses the fire box and the combustion chamber is secured to the header, 13, the back head, 5, and the mud ring, 2, said wrapper performing, primarily the function of a rigid connecting member for the fire box and boiler barrel, and secondarily, that of a closure or housing for the top of the fire box, 25 to prevent the escape of gases of combustion therefrom. Suitable lagging or insulating material, 21, is applied, between the outsides of the water tubes, 3 and 3^a, and the wrapper sheet.

30 Boilers embodying my invention present the advantage of decreasing the diameter of the boiler barrel, B, with a resultant reduction in weight; the elimination of structural difficulties and increase in the factor of 35 safety; and the provision of separate circulation systems for the fire box and the boiler barrel, thereby increasing the rapidity of circulation and mechanically controlling the circulation to prevent interference of the 40 water circuits, all of which features effect a substantial increase in efficiency. The boiler is of a form adapted for carrying the highest steam pressures now utilized in service or contemplated in locomotive operation.

45 I claim as my invention and desire to secure by Letters Patent:

1. In a boiler of the locomotive type, the combination of a fire box, the sides of 50 which are formed of water tubes; a barrel, extending forwardly from the forward end of the fire box; a drum, extending forwardly from the rear end of the fire box and communicating with the side water tubes thereof; means, connecting the interior of the 55 forward end of the drum with the interior of the forward end of the barrel; and supplemental means, establishing circulation be-

tween the rear and the forward portions of the barrel.

2. In a boiler of the locomotive type, 60 the combination of a fire box, the sides of which are formed of water tubes; a barrel, extending forwardly from the forward end of the fire box; a drum, extending forwardly from the rear end of the fire box and communicating with the side water tubes thereof and with the barrel; headers, located at the opposite ends of the barrel; and supplemental means, establishing steam circulation, through said headers between the rear 65 and the forward portions of the barrel. 70

3. In a boiler of the locomotive type, 75 the combination of a fire box, the sides of which are formed of water tubes; a barrel, extending forwardly from the forward end of the fire box; a drum, extending forwardly from the rear end of the fire box and communicating with the side water tubes thereof and with the barrel; headers, communicating with the opposite ends of the barrel; 80 and lateral drums, connected, at their, ends to the interior of said headers.

4. In a boiler of the locomotive type, 85 the combination of a fire box, the sides of which are formed of water tubes; a barrel; 90 headers, disposed at the ends of the barrel, and in communication therewith at their lower portions; a drum, extending forwardly from the rear end of the fire box, and in communication with said water tubes and with one of said headers; a water circuit, comprising said headers; water connections between the upper portions of the headers, and said barrel, whereby steam generated in such circuit is supplied to the drum; and a second water circuit, comprising feed water connections, delivering water to the side water tubes from the barrel, said drum and said header establishing communication between said 95 drum and barrel. 100

5. In a boiler of the locomotive type, 105 the combination of a fire box, the sides of which are formed of water tubes; a barrel, extending forwardly from the forward end of the fire box; a drum, extending forwardly from the rear end of the firebox; headers, located at the ends of the barrel, one of which communicates with the drum; side drums, connecting the upper portions of the headers; and two water connections, leading independently from the barrel to different locations in the side water tubes. 110

ALFRED W. BRUCE.
